UNITED STATES PATENT OFFICE.

LUCILLE BENTZ, OF SEATTLE, WASHINGTON.

DESIGN FOR A BROOCH, BUTTON, OR SIMILAR ARTICLE.

43,810.

Specification for Design.

Patented Apr. 1, 1913.

Application filed January 2, 1913. Serial No. 739,888. Term of patent 7 years.

To all whom it may concern:

Be it known that I, LUCILLE BENTZ, a citizen of the United States, residing at Seattle, in the county of King and State of Washington, have invented a new, original, and ornamental Design for a Brooch, Button, or Similar Article, of which the following is a specification, reference being had to the accompanying drawing, forming a part thereof.

The figure is a plan view of a brooch showing my new design.

I claim:

The ornamental design for a brooch, button or similar article, as shown.

LUCILLE BENTZ.

Witnesses:

E. PETERSON,
HORACE BARNES.
